UNITED STATES PATENT OFFICE.

CLARENCE H. HOWARD, OF ST. LOUIS, MISSOURI, ASSIGNOR TO LOCOMOTIVE TENDER FRAME COMPANY, OF ST. LOUIS, MISSOURI, A CORPORATION OF DELAWARE.

CAST-STEEL UNDERFRAME FOR CARS.

1,035,194.

Specification of Letters Patent. Patented Aug. 13, 1912.

Application filed June 15, 1911. Serial No. 633,377.

To all whom it may concern:

Be it known that I, CLARENCE H. HOWARD, a citizen of the United States, residing at St. Louis, Missouri, have invented a certain 5 new and useful Improvement in Cast-Steel Underframes for Cars, of which the following is a full, clear, and exact description, such as will enable others skilled in the art to which it appertains to make and use the 10 same, reference being had to the accompanying drawings, forming part of this specification, in which—

Figure 1 is a top plan view of the improved tender underframe, and Fig. 2 is a 15 longitudinal sectional view taken through the center of the underframe.

This invention relates to new and useful 20 improvements in cast steel underframes for locomotive tenders and other railway rolling stock, the object being to construct a device of the character described which can be cast in one piece and which embodies a 25 novel arrangement of flanged bars and reinforcing webs, all as will hereinafter be described and pointed out in the claims.

In the drawings, 1 indicates the longitudinal members, 2 the transverse members, 3 the bolster members, 4 the front end sill, and 5 the rear end sill. Each of these end 30 sills is provided with an inwardly extending flange 7 forming a strengthening web and gussets for the longitudinal members. The front end sill is provided with a pocket 8 on its under side for receiving the pocket 35 coupler, the top wall of said pocket being formed by the bottom flange of the dead block, while the bottom wall of said coupler is substantially a continuation of the bottom flange of the end sill. Due to the 40 high location of this pocket coupler, the central longitudinal members have their bottom flanges deflected upwardly, as shown in Fig. 2, to meet and strengthen the walls of the pocket coupler.

45 The centrally located transverse member 2 is strengthened by horizontally disposed flanges 9 and 10, the latter being formed integral with a box-like housing 11 open on its under side for accommodating parts of 50 the water scoop by which water may be taken from a trough and introduced into the tank when the locomotive is under way.

As illustrated immediately in front of the rear bolster, the draft sills are fitted for the 55 reception of transom draft gear, which is,

in the construction of the car, introduced from below. It will be noted that the flanges 1^a of the draft members are normally directed inwardly from the webs throughout the length of said draft members. At the 60 point 1^b where the draft gear is to be introduced, however, the lower flanges of the draft members are diverted from the inner sides of the webs to the outer side so that none, or a comparatively small projection 65 1^c remains presented inwardly. This construction permits of the introduction of the transom draft gearing, while not weakening the draft members at this point.

12 indicates the floor of the tender which 70 is usually of wood, and projecting up through this floor is an abutment 13 slightly in advance of the central transverse member, the upper end of this abutment being curved rearwardly, as shown, so as to engage 75 the nose of the tank 14 at the rear of the coal receptacle. In this manner the tank is anchored to the underframe. The ends of the end sill terminate short of the sides of the frame, so as to accommodate steps 15, 80 shown in dotted lines, which steps are preferably bolted in position. The end sill extends up above the plane of the longitudinal members of the car so as to provide abutments for the end wall of the tank, and 85 in addition the integral web 13 engages the nose of the tank at the rear of the coal bin so that the tank is not only held against longitudinal movement by the end sills, but is anchored to the underframe by the web 90 13, said web extending up into the coal bin and preventing lateral movement of the tank on the underframe.

A tender frame constructed as above described is exceedingly simple and strong, 95 and is not liable to be broken in service. It may readily be molded, and, as the parts are all cast integral, the absence of fastening devices prevents the parts from becoming loose.

100 I claim:

1. In a cast steel underframe, the combination of bolsters and longitudinal members integrally connected to said bolsters, said longitudinal members having flanges at 105 their upper and lower edges on one side only throughout part of their length and on both sides throughout part of their length.

2. In a cast steel underframe, the combination of bolsters and longitudinal mem- 110

- bers integral therewith, all of said parts being flanged, and the bottom flanges of said longitudinal members near the bolsters being cut away.
5. 3. In a cast steel underframe, the combination of flanged longitudinal members having inwardly presented flanges throughout the greater portion of their length, and outwardly presented flanges at points adjacent the bolsters.
10. 4. In a cast steel underframe, the combination with bolster members, of longitudinal members flanged throughout their

length, the bottom flanges adjacent the bolster being cut away and said members being provided with outwardly presented flanges coincident with said cut away portions.

15. In testimony whereof I hereunto affix my signature in the presence of two witnesses, 20 this 13th day of June, 1911.

CLARENCE H. HOWARD.
